TROMBONE ATTACHMENT

Filed May 1, 1922

FIG. 1.

FIG. 2.

FIG. 3.

Leon C. Benson.
INVENTOR

John W. Davis, Jr.
WITNESS

by Victor J. Evans
ATTORNEY

UNITED STATES PATENT OFFICE.

LEON C. BENSON, OF PHILADELPHIA, PENNSYLVANIA.

TROMBONE ATTACHMENT.

Application filed May 1, 1922. Serial No. 557,622.

To all whom it may concern:

Be it known that I, LEON C. BENSON, a citizen of the United States, residing at Philadelphia, in the county of Philadelphia and State of Pennsylvania, have invented new and useful Improvements in Trombone Attachments, of which the following is a specification.

This invention relates to trombones and 10 it has more particular references to slide trombones, the primary object being to provide a novel attachment therefor whereby said trombone may be more easily balanced and held by the player.

15 Another object of this invention is the provision of a novel attachment for slide trombones which is adapted for ready adjustment and positioning on the instrument with a minimum expenditure of time and 20 labor.

A further object of this invention is the provision of a novel attachment for trombones of the type referred to which is simple in construction, cheap to manufacture, 25 and very effective in use for the purpose for which it has been designed.

With the foregoing and other objects in view as will be more clearly apparent from the following description my invention essentially 30 consists of a substantially heavy member having threaded into its longitudinal ends telescopic sections which are adapted for gripping engagement with the tubular body portions of the main wind-pipe or for 35 disposition wherever desired on the instrument so as to effectively balance the same and thereby relieve the player from undue physical strain.

In the further disclosure of the invention 40 reference is to be had to the accompanying sheet of drawings constituting a part of this specification and in which like characters of reference designate the same or corresponding parts in all the views.

45 Figure 1 is a side view of a slide trombone having my novel attachment applied thereto.

Figure 2 is a longitudinal section through my novel trombone attachment, the same being drawn to an enlarged scale for the 50 sake of clearness; and,

Figure 3 is an outside view of the same taken at right angles to the preceding figure.

Referring more particularly to the views 55 Figure 1 illustrates an ordinary slide trombone including bell portion 4, wind-pipe 5 and playing slide 6 having a cross-bar 7

by means of which the playing of the instrument is effected when said cross-bar is clasped in the right hand. Now, it is a well known fact that when an instrument of the kind referred to is being played the bell 60 4 and playing slide 6 are much heavier than the end of the instrument having the bend 8 therein, and in order to balance the horn the left hand and wrist are placed under considerable strain. In order to overcome the foregoing objection and to balance the 65 trombone so that no undue strain is placed on either hand of the operator I employ a counter-balance member designated generally by the numeral 9.

This counter-balance member 9 comprises a main or body portion 10 substantially solid and cylindrical. Longitudinally of the aforesaid body portion 10 and at each end 70 thereof I make borings 11, 12, the inner ends whereof are slightly counterbored and screw-threaded at 13, 14 respectively. Slidably fitting the aforesaid borings 11, 12 are shank members 15, 16 respectively, the outer ends 75 whereof are made of saddle formation as indicated at 17 and each saddle portion 17 is appropriately protected with a liner 18 of leather or other appropriate material which will prevent damage to the finished surface of 80 the instrument when applied thereto. The inner ends of the aforesaid shank members 15, 16 are respectively screw-threaded at 19, 20 for threaded engagement into the aforesaid counter-borings 13, 14 and it is 85 to be particularly noted at this point that said threaded portions 19, 20 are respectively right and left hand screws.

In applying the attachment to the instrument it will be readily seen that the shank 95 members 15, 16 are secured inwardly relative to the body portion 10 so that the saddle portions 17 can be easily passed between and placed in alignment with opposed tubular portions 21, 21' adjacent the curved 100 end or bend 8 of the instrument, rotation of the body portion 10 of the device 9 extending the saddle portions 17 between said tubular portions 21, 21' until the liners 18 grip or impinge the outer faces thereof. Obviously 105 the outer surface of the body portion may be roughened, serrated or scored so as to provide a suitable hand-hold or grip to manipulate the device.

Now it will be perfectly clear to those acquainted with the art to which this invention appertains that by my invention I have pro- 110

vided a simple and efficient counter-balance attachment for musical instruments of the nature referred to, its use, advantages and application thereto being perfectly obvious without further explanation or description. While I have shown and described a preferred embodiment of my invention I do not desire to be limited to the precise details enumerated as it will be obvious the same are susceptible of minor changes and variations without departing from the spirit and scope of said invention as more specifically defined by the appended claims.

Having described my invention, what I claim as new and desire to secure by Letters Patent is:

1. A counter-balance attachment for trombones comprising a substantially solid elongated body portion, axial longitudinal borings in the ends of said body portion, the inner ends whereof are screw-threaded in reverse direction, shank members for fitting in the aforesaid borings and having their in-

ner ends reduced and screw-threaded for engagement in the aforesaid threaded counter-borings, the outer ends of said shank members being adapted for gripping engagement between opposed tubular portions of the trombone. 25

2. A counter-balance attachment for trombones comprising a substantially solid elongated body portion, axial longitudinal borings in the ends of said body portion, the inner ends whereof are screw-threaded in reverse direction, shank members for fitting 30 in the aforesaid borings and having their inner ends reduced and screw-threaded for engagement in the aforesaid threaded counter-borings, the outer ends of said shank members being of saddle formation and 35 lined with leather for gripping engagement between opposed tubular portions of the trombone adjacent its bend.

In testimony whereof I affix my signature.

LEON C. BENSON.
